OTHER PUBLICATIONS

U.S. Appl. No. 291624,451, filed Nov. 1, 2017 in the name of Newtl.

Primary Examiner — Darlington Ly(74) *Attorney, Agent, or Firm* — Carter, Deluca & Farrell LLP**(57) CLAIM**

The ornamental design for a wall panel with window frame, as shown and described.

DESCRIPTION

The patent or application file contains at least one drawing executed in color. Copies of this patent or patent application publication with color drawing(s) will be provided by the Office upon request and payment of the necessary fee.

FIG. 1 is an isometric rear side perspective detailed view of a wall panel with window frame of a bus including a handrail and a bell in accordance with the present design; FIG. 2 rear elevational view thereof;

FIG. 3 is isometric front perspective view thereof;

FIG. 4 is a left side elevational view thereof; and,

FIG. 5 is a right side elevational view thereof.
